UNITED STATES PATENT OFFICE.

EDSON O. SESSIONS, OF CHICAGO, ILLINOIS.

LOCKING-SWITCH.

1,221,611.

Specification of Letters Patent.

Patented Apr. 3, 1917.

Application filed July 10, 1916. Serial No. 108,302.

To all whom it may concern:

Be it known that I, EDSON O. SESSIONS, a citizen of the United States, residing at Chicago, in the county of Cook and State 5 of Illinois, have invented a certain new and useful Improvement in Locking-Switches, of which the following is a specification.

My invention relates particularly to an improved construction of locking switch for 10 use in connection with alternating currents of large capacity, for which purpose it is desirable to lock the switch in its closed position in order to prevent accidental opening of the switch, as for example, when an undue rush 15 of current flows through the same. In carrying out my invention, the switch is provided with an operating handle and also with a lock operated thereby, the relation between the two parts being such that the 20 motion of the lock is greater angularly than the motion of the handle required to operate it. In closing the switch, the lock is free to positively engage its catch to secure and hold the switch in its closed position.

25 My invention is shown in its preferred embodiment in the accompanying drawings, in which—

Figure 1 shows the complete switch in side view in closed position,

30 Fig. 2 shows in an enlarged scale the operating handle and locking device, shown partially in section to illustrate the construction, and

Fig. 3 is a sectional view of the parts 35 shown in Fig. 2 taken along the line 3—3.

Similar numerals refer to similar parts throughout the several views.

As shown in Fig. 1, the switch is mounted upon a supporting board or panel 10 and 40 consists of a pivot clip 11 to which the switch blade 12 is pivotally secured at 13, and clip jaws 14 also supported upon the base 10 for receiving the switch blade 12 when the switch is closed.

45 As more clearly seen in Figs. 2 and 3, the end of the switch blade 12, projecting beyond the clip jaws 14, has secured thereto by suitable rivets or screws a housing 15, through which a rod 16 extends for supporting at its ends a yoke 17 to which the handle 18 is rigidly secured by a metal rod 19 extending therethrough. The rod 19 is threaded at its inner end to engage a nut 20, used to hold the handle in place, and the end of 50 the rod projects beyond the nut 20 through a slot 21 formed in the outer wall of the

housing 15. A second rod 22 extends across the housing 15 in parallel relation to the rod 16 and has mounted thereon a locking latch 23 provided at its outer end, which projects through the housing, with a hook 24 for engaging when the switch is in its closed position, a catch 25 secured to the base of the clip jaws 14. The latch 23 is provided with a short arm 26 extending substantially at right angles to the body portion of the latch and through this arm a rod 27 extends which, as indicated in Fig. 3, is provided near its ends with grooves 28. Each groove 28 is engaged by one end of a helical spring 29, the other end of which is secured to the housing by a rod 30 extending across the housing as indicated. The arm 26 is disposed centrally of the switch, so that it is engaged by a projection 31 extending into the housing 15 from the rod 19 when the handle 18 is moved relatively to the housing to open the switch.

From the above it will be observed that I have provided a simple and effective construction by which an operating handle is secured directly to a switch, so that the natural motion of the handle in opening the switch first moves the switch lock to its releasing position, after which continued motion of the handle opens the switch. Furthermore, motion of the handle in the reverse direction to close the switch permits the switch lock to return to its engaging position, so that when the switch is forced 90 into engagement with the clip jaws 14, the lock or latch may readily yield against the action of the springs 29 to engage the catch 25.

While I have shown the switch in Fig. 3 95 as consisting of a plurality of blades 12, it will be understood I do not limit myself to any particular number of blades as the handle and locking mechanism may be used upon any switch of this type regardless of 100 the number of blades.

While I have shown my invention in the particular embodiment above described, I do not, however, limit myself to this exact construction as I may employ any equivalents thereof known to the art at the time of the filing of this application, without departing from the scope of the appended claims.

What I claim is:

1. In a locking switch, the combination of a pair of posts, a switch blade pivoted to

2

one of said posts, contact clips carried by the other post for engaging said blade in its closed position, a housing carried by the free end of said blade, a locking latch pivotally supported in and extending from said housing, a catch carried by said other post for engaging said latch to retain said blade in its closed position, and an operating handle pivotally supported on said housing and extending therethrough to engage said latch to move said latch from engagement with said catch when said handle is operated to open said switch.

2. In a locking switch, the combination of 15 a pair of posts, a switch blade pivoted to one of said posts, contact clips carried by the other post for engaging said blade in its closed position, a housing carried by the free end of said blade, a locking latch pivotally supported in and extending from said housing, a catch carried by said other post for engaging said latch to retain said blade in its closed position, and an operating handle pivotally supported on said housing and 20 extending therethrough to engage said latch to move said latch from engagement with said catch when said handle is operated to open said switch, said latch being in the form of a bell crank lever having a long arm 25 provided with a hook for engaging said catch and a short arm lying in the path of the handle extension to be operated thereby.

3. In a locking switch, the combination of 35 a pair of posts, a switch blade pivoted to one of said posts, contact clips carried by the other post for engaging said blade in its closed position, a housing carried by the free end of said blade, a locking latch pivotally supported in and extending from said 40 housing, a catch carried by said other post for engaging said latch to retain said blade in its closed position, an operating handle pivotally supported on said housing and extending therethrough to engage said latch 45 to move said latch from engagement with said catch when said handle is operated to open said switch, said latch being in the form of a bell crank lever having a long arm provided with a hook for engaging said 50 catch and a short arm lying in the path of the handle extension to be operated thereby, and a coil spring tending to hold said latch in its engaging position.

4. In a locking switch, the combination of 55 a pair of posts, a switch blade pivoted to one of said posts, contact clips carried by the other post for engaging said blade in its closed position, an inclosed box shaped housing secured to the free end of said blade, 60 said housing having a cylindrical end wall, two rods supported by said housing substantially parallel with the pivotal axis of said blade, a yoke pivotally supported on one of said rods outside of and around the cylindrical end of said housing, a locking latch 65

pivotaly supported within the housing upon the other of said rods and extending through said housing, a catch carried by said other post for engaging said latch when the switch blade is closed, and an operating handle secured to said yoke and extending through said housing to engage and release said latch when said handle is operated.

5. In a locking switch, the combination of 70 a pair of posts, a switch blade pivoted to one of said posts, contact clips carried by the other post for engaging said blade in its closed position, an inclosed box shaped housing secured to the free end of said blade, 75 said housing having a cylindrical end wall, two rods supported by said housing substantially parallel with the pivotal axis of said blade, a yoke pivotally supported on one of said rods outside of and around the cylindrical end of said housing, a locking 80 latch pivotally supported within the housing upon the other of said rods and extending through said housing, a catch carried by said other post for engaging said latch when the switch blade is closed, and an operating handle 85 secured to said yoke and extending through said housing to engage and release said latch when said handle is operated, said latch being in the form of a bell crank lever having a long arm provided with a hook 90 for engaging said catch and a short arm lying in the path of the handle extension to be operated thereby.

6. In a locking switch, the combination of 95 a pair of posts, a switch blade pivoted to one of said posts, contact clips carried by the other post for engaging said blade in its closed position, an inclosed box shaped housing secured to the free end of said blade, 100 said housing having a cylindrical end wall, two rods supported by said housing substantially parallel with the pivotal axis of said blade, a yoke pivotally supported on one of said rods outside of and around the cylindrical end of said housing, a locking 105 latch pivotally supported within the housing upon the other of said rods and extending through said housing, a catch carried by said other post for engaging said latch when the switch blade is closed, an operating handle 110 secured to said yoke and extending through said housing to engage and release said latch when said handle is operated, said latch being in the form of a bell crank lever having a long arm provided with a hook for 115 engaging said catch and a short arm lying in the path of the handle extension to be operated thereby, and a coil spring tending to hold said latch in its engaging position.

7. In a locking switch, the combination of 120 a pair of posts, a switch blade pivoted to one of said posts, contact clips carried by the other post for engaging said blade in its closed position, a housing carried by the free end of said blade, a locking latch piv- 125

130

totally supported in and extending from said housing, a catch carried by said other post for engaging said latch to retain said blade in its closed position, an operating handle 5 pivotally supported on said housing and extending therethrough to engage said latch to move said latch from engagement with said catch when said handle is operated to open said switch, said latch being in the 10 form of a bell crank lever having a long arm provided with a hook for engaging said catch and a short arm lying in the path of the handle extension to be operated thereby, a rod extending through the short end of 15 said bell crank lever, and a spring extending from each end of said rod to said housing to hold said latch in its engaging position.

8. In a locking switch, the combination 20 of a pair of posts, a switch blade pivoted to one of said posts, contact clips carried by the other post for engaging said blade in its closed position, a housing carried by the free end of said blade, a locking latch 25 pivotally supported in and extending from said housing, a catch carried by said other post for engaging said latch to retain said blade in its closed position, an operating handle pivotally supported on said housing 30 and extending therethrough to engage said latch to move said latch from engagement with said catch when said handle is operated to open said switch, a rod extending through said latch, and a spring extending 35 from each end of said rod to said housing to hold said latch in its engaging position.

9. In a locking switch, the combination of 40 a pair of posts, a switch blade pivoted to one of said posts, contact clips carried by the other post for engaging said blade in its closed position, a bell crank lever pivotally connected to the free end of said blade and having a first arm formed into a latch and a second arm for operating said latch, a 45 catch carried by said other post for engaging said latch when the blade is in its closed position, and an operating handle carried by and movable relatively to the free end of said blade, said handle having a portion for 50 engaging said second arm, whereby motion of said handle relatively to said blade moves said latch to its releasing position.

10. In a locking switch, the combination 55 of a pair of posts, a switch blade pivoted to one of said posts, contact clips carried by the other post for engaging said blade in its closed position, a bell crank lever pivotally connected to the free end of said blade and having a first arm formed into a latch and a 60 second arm for operating said latch, a catch carried by said other post for engaging said latch when the blade is in its closed position, and an operating handle carried by and movable relatively to the free end 65 of said blade, said handle having a portion

for engaging said second arm, whereby motion of said handle relatively to said blade moves said latch to its releasing position, said second arm being shorter than said first arm, whereby the motion of said latch when operated by said handle is greater than the motion of said handle. 70

11. In a locking switch, the combination of a pair of posts, a switch blade pivoted to one of said posts, contact clips carried by the other post for engaging said blade in its closed position, a bell crank lever pivotally connected to the free end of said blade and having a first arm formed into a latch and a second arm for operating said latch, a 80 catch carried by said other post for engaging said latch when the blade is in its closed position, and an operating handle carried by and movable relatively to the free end of said blade, said handle having a portion for 85 engaging said second arm, whereby motion of said handle relatively to said blade moves said latch to its releasing position, said handle being pivoted to engage said second arm with a lever arm longer than the 90 lever arm of said second arm.

12. In a locking switch, the combination of a pair of posts, a switch blade pivoted to one of said posts, contact clips carried by the other post for engaging said blade in its 95 closed position, a bell crank lever pivotally connected to the free end of said blade and having a first arm formed into a latch and a second arm for operating said latch, a catch carried by said other post for engaging said latch when the blade is in its closed position, an operating handle carried by and movable relatively to the free end of said blade, said handle having a portion for 100 engaging said second arm, whereby motion of said handle relatively to said blade moves said latch to its releasing position, and a spring for holding said latch in its engaging position. 105

13. In a locking switch, the combination of a pair of posts, a switch blade pivoted to one of said posts, contact clips carried by the other post for engaging said blade in its closed position, a bell crank lever pivotally connected to the free end of said blade and having a first arm formed into a latch and a second arm for operating said latch, a catch carried by said other post for engaging said latch when the blade is in its closed position, an operating handle carried by and movable relatively to the free end of said blade, said handle having a portion for 110 engaging said second arm, whereby motion of said handle relatively to said blade moves said latch to its releasing position, said second arm being shorter than said first arm, whereby the motion of said latch when operated by said handle is greater than the motion of said handle, and a spring for holding 115 said latch in its engaging position. 120

125

130

14. In a locking switch, the combination of a pair of posts, a switch blade pivoted to one of said posts, contact clips carried by the other post for engaging said blade in its closed position, a bell crank lever pivotally connected to the free end of said blade and having a first arm formed into a latch and a second arm for operating said latch, a catch carried by said other post for engaging said latch when the blade is in its closed position, an operating handle carried by and movable relatively to the free end of said

blade, said handle having a portion for engaging said second arm, whereby motion of said handle relatively to said blade moves 15 said latch to its releasing position, said handle being pivoted to engage said second arm with a lever arm longer than the lever arm of said second arm, and a spring for holding said latch in its engaging position. 20

In witness whereof, I hereunto subscribe my name this 6th day of July, A. D. 1916.

EDSON O. SESSIONS.
